PINION STRAIGHTENING DEVICE

Walter Walczak, Edmonton, Alberta, Canada

Application April 23, 1956, Serial No. 580,111

12 Claims. (Cl. 153—32)

My invention relates to new and useful improvements in devices for straightening pinions, particularly pinions of watches, clocks and the like, the principal object and essence of my invention being to provide a device of the character herewithin described which is adapted to receive the pinion, to support same perfectly horizontally with relation to the anvils, and to provide clamping means to clamp the pinion between the anvils thereby straightening same in a plane perpendicular to the pinion pin.

A further object of my invention is to provide a device of the character herewithin described which includes levelling means both on the pinion carrying jig and the device thereby enabling the operator to ensure that the pinion is held horizontally and that the anvils also are horizontal.

Yet another object of my invention is to provide a device of the character herewithin described which contains a plurality of anvils adapted to receive pinions of different sizes.

A still further object of my invention is to provide a device of the character herewithin described which is extremely efficient in operation, and which furthermore permits an operator to straighten pinions rapidly and accurately.

Yet another object of my invention is to provide a device of the character herewithin described which is simple in construction, economical in manufacture, and otherwise well suited to the purpose for which it is designed.

With the foregoing objects in view, and such other objects and advantages as will become apparent to those skilled in the art to which this invention relates as this specification proceeds, my invention consists essentially in the arrangement and construction of parts all as hereinafter more particularly described, reference being had to the accompanying drawings in which:

Figure 1 is a side elevation of my device.

Figure 2 is a side elevation of my device taken at right angles to Figure 1 and sectioned in part.

Figure 3 is a top plan view of Figure 1.

Figure 4 is a front elevation of the jig and pinion per se.

In the drawings like characters of reference indicate corresponding parts in the different figures.

Proceeding now to describe my invention in detail, it will be seen upon reference to the accompanying drawings that it consists primarily of a base collectively designated 1, a head piece collectively designated 2, and a jig collectively designated 3.

Specifically, the base 1 consists of a substantially triangular base plate 4 having a substantially cylindrical body portion 5 extending upwardly from the centre thereof. Levelling screws 6 screw-threadably engageable within the corners 7 of the triangular base plate, terminate in surface engaging feet 8 and permit adjustment of the base, the purpose of which will hereinafter be described.

2

Surmounting the cylindrical main body portion 5 is a plate 9 parallel with the base plate 4 and having, in this embodiment, three anvils 10 extending outwardly therefrom. The aforementioned cylindrical body portion 5 is apertured centrally as at 11 and is provided with a sleeve 12 bearably slidably therein, it being noticed that the upper end 13 of the sleeve extends above the plane of the upper surface 14 of the plate 9.

The head piece 2 consists of a central hub 15 recessed centrally as at 16 upon the under surface thereof, it being noticed that the head piece is receivable by the recess 16 upon the extending portion 13 of the sleeve so that the extending portion 13 supports the head piece 2 being rigidly attached thereto.

Upper anvils 17 extend outwardly from the central hub 15 of the head piece and correspond to the aforementioned anvils 10 there being three of such pairs of anvils in the present embodiment.

A clamping post 18 surmounted by a knurled knob 19 is freely engageable within an aperture 20 formed in the hub 15 and is rotatable within this aperture but is restricted against downward movement therein by means of fixed washer 21 being secured to the post 18 and engaging the upper surface 22 of the hub 15.

Post 18 extends downwardly through the sleeve 12 and is screw-threaded at the lower end 23 thereof. The base 24 of the cylindrical body portion 5 is apertured centrally and screw-threaded to receive this screw-threaded end 23 as clearly illustrated in Figure 2.

A spring 25 surrounds the post 18 and reacts between the base of aperture 11 and the underside of the recess 16 thus normally urging the head piece upwardly when the clamping post is unreserved.

In order to prevent rotation of the head piece and also to limit the upward movement thereof and to prevent displacement of the head piece from the sleeve 12, I provide a knurled bolt 26 extending through plate 9 and being free to rotate therein and being screw-threadably engageable within the head piece as clearly illustrated in Figure 2 and it will be appreciated that rotation of this bolt 26 controls the spacing between the pairs of anvils and prevents the aforementioned displacement.

The aforementioned jig 3 consists of an upper stem 27 and a lower stem 28 between which is formed an open centered main body portion 29. A pinion carrying pin 30 extends downwardly within the portion 29 from the stem 27 and a further pin 31 extends upwardly from the stem 28, it being observed that the pin 31 is attached to a screw 32 screw-threadably engageable within the stem 28. These pins are adapted to hold a pinion 33 therebetween as clearly illustrated, it being understood that the points 34 are adapted to enter the aperture within the pinion normally receiving the pinion pin. Finally, it will be noticed that a conventional bubble level 35 surrounds the stem 27.

In operation, the pinion to be straightened is held between the pins of the jig as illustrated in Figure 4 whereupon the jig is slid over a convenient pair of anvils which are apertured or slotted as at 36' to receive the pins 30 and 31 so that the pinion 33 is situated between the anvils as clearly illustrated in Figure 2. The different anvils 10 are provided with slots with which to take pinions of varying sizes.

A further conventional bubble level 36 is secured to an extension of plate 9 thus enabling the operator, via the levelling screws 6, to ensure that the plate 9 is completely horizontal, and also to ensure that the pinion 33 being held between the anvils is also horizontal, this latter being checked by the bubble level 35 on the jig.

The clamping post 18 is then rotated so that the head piece 2 is moved downwardly towards the plate 9 thus causing the pinion to be clamped between the anvils 10.

and 17, continued pressure causing same to be straightened and aligned in a plane at right angles to perpendicular axis thereof, the engagement of sleeve 13 within the base of aperture 11 ensuring that the surfaces of the plate 9 and the head piece 2 remain parallel.

After the clamping post has been tightened sufficiently to straighten the pinion, same may be released, spring 25 urges the head piece upwardly to the limits defined by the position of the adjusting bolt 26 whereupon the jig may be removed and the pinion pivot post replaced.

Since various modifications can be made in my invention as hereinabove described, and many apparently widely different embodiments of same made within the spirit and scope of the claims without departing from such spirit and scope, it is intended that all matter contained in the accompanying specification shall be interpreted as illustrative only and not in a limiting sense.

What I claim as my invention is:

1. A device for straightening pinions and the like comprising in combination a base, a fixed anvil on said base, a movable head piece situated for vertical movement above said base and supported thereby, an anvil plate on said head piece superjacent to said fixed anvil, means associated with said anvils for supporting a pinion therebetween, and means co-operating between said head piece and said base adapted to move said head piece towards and away from said base, said means for supporting said pinion between said anvils including said anvils being slotted at the outer ends thereof, and a jig for supporting said pinion, said jig comprising an upper stem and a lower stem, an open-centred main body portion between said stems, pinion carrying pins extending from each of said stems within said open-centred main body portions, one of said pins being adjustable lengthwise, said pins adapted to be received by said slots.

2. The device according to claim 1 in which said base is apertured vertically, guide means extending above said base within said aperture, said head piece being recessed and affixed to said guide means.

3. The device according to claim 2 in which said means co-operating between said head piece and said base includes a clamping post freely rotatable within said head piece, said clamping post extending downwardly within said aperture within said base, said clamping post being screw-threaded at the lower end thereof and being screw-threadably engageable within a corresponding screw-threaded aperture at the base of first-mentioned aperture.

4. The device according to claim 3 which includes spring means surrounding said clamping post and reacting between said base and said head piece.

5. The device according to claim 1 in which said base includes a base plate, levelling screws on said base plate and a main body portion extending upwardly from said base plate, a plate surmounting said main body portion, and a plurality of anvils formed on said plate, said movable head piece also including a corresponding plurality of anvils formed thereon each one superjacent one of said first-mentioned anvils on said plate, and means to restrain vertical movement of said head piece within limits.

6. The device according to claim 1 which includes a levelling indicator on said jig.

7. The device according to claim 1 which includes a levelling indicator on said base.

5 8. The device according to claim 6 which includes also a levelling indicator on said base.

9. The device according to claim 2 in which said base includes a base plate, levelling screws on said base plate and a main body portion extending upwardly from said 10 base plate, a plate surmounting said main body portion, and a plurality of anvils formed on said plate, said movable head piece also including a corresponding plurality of anvils formed thereon each one superjacent one of said first-mentioned anvils on said plate, and means to 15 restrain vertical movement of said head piece within limits.

10. The device according to claim 3 in which said base includes a base plate, levelling screws on said base plate and a main body portion extending upwardly from said 20 base plate, a plate surmounting said main body portion, and a plurality of anvils formed on said plate, said movable head piece also including a corresponding plurality of anvils formed thereon each one superjacent one of said first-mentioned anvils on said plate, and means to 25 restrain vertical movement of said head piece within limits.

11. The device according to claim 2 in which said means for supporting said pinion between said anvils includes said anvils being slotted at the outer ends thereof, and a jig for supporting said pinion, said jig comprising an upper stem and a lower stem, an open-centred main body portion between said stems, pinion carrying pins extending from each of said stems within said open-centred main body portions, one of said pins being adjustable lengthwise, said pins adapted to be received by said slots.

30 12. The device according to claim 3 in which said means for supporting said pinion between said anvils includes said anvils being slotted at the outer ends thereof, and a jig for supporting said pinion, said jig comprising an upper stem and a lower stem, an open-centred main body portion between said stems, pinion carrying pins extending from each of said stems within said open-centred main body portions, one of said pins being adjustable lengthwise, said pins adapted to be received by said slots.
